CLAIM

The ornamental design for a lotion dispenser, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top front right perspective view of a lotion dispenser showing our new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.

A characteristic feature of the design resides in the color of the surface of the lotion dispenser being pink, which pink color is defined according to the PANTONE™ color scale as 196C.
